D. W. BOWERS

CRE ROASTING APPARATUS

Filed Aug. 6, 1927

Inventor

D.W.Bowers

By Watson E. Coleman Attorney

UNITED STATES PATENT OFFICE.

DANA W. BOWERS, OF WILDERNESS, VIRGINIA.

ORE-ROASTING APPARATUS.

Application filed August 6, 1927. Serial No. 211,230.

This invention relates to ore roasting apparatus and more particularly to an ore roasting apparatus especially intended for use in roasting gold bearing sulphide ores.

5 An important object of the invention is the production of a device whereby the ore may be roasted by continuous and rapid passage through a retort to oxidize base metals and condition the ore for treatment in an extraction plant.

10 A further object of the invention is to provide a device of this character in which the gases formed in roasting are separated and washed and in the washing process, intermingled with steam, so that they are properly conditioned for delivery to a sulphuric acid plant for conversion into commercial sulphuric acid.

15 A still further object of the invention is to provide a device of this character which will be extremely simple in its construction and operation, which will not be critical either as to temperature or to the speed of passage of the ores therethrough and which 20 will be durable and efficient in service.

25 These and other objects I attain by the construction shown in the accompanying drawing, wherein for the purpose of illustration is shown a preferred embodiment of my invention and wherein:—

Figure 1 is a vertical sectional view through ore roasting apparatus constructed in accordance with my invention;

30 Figure 2 is a section on the line 2—2 of Figure 1.

35 Referring now more particularly to the drawings, the numeral 10 generally designates a cylindrical retort wall of refractory material and having its upper end closed, as 40 at 11. The refractory wall is preferably enclosed by an outer metallic case 12 embodying at its lower end a flange 13, by means of which the refractory wall is supported. Surrounding the retort in slightly 45 spaced relation to the metallic wall 12 there- 50 of is a cylindrical condenser casing 14 hav- 55 ing conical upper and lower ends 15 and 16, which communicate with an exhaust tube 17 and an outlet pipe 18. The exhaust pipe 55 60 65 70 75 80 85 90 95 100 105 110

117 preferably leads directly to a commercial sulphuric acid plant (not shown), while the outlet 18 preferably leads directly to an extraction plant. Both the condenser casing and retort are supported by upwardly con- 65 verging braces 19 which, intermediate their 70 75 80 85 90 95 100 105 110

ends, are secured to the lower conical extension of the condenser casing, as at 20, and at their upper ends are secured to the flange 13.

80 A blower 21 has its exhaust pipe 22 ex- 60 tended through and sealed to the condenser wall and into the wall of the retort 10, so that incoming air enters the retort tangentially. A fuel feed pipe 23 is in communica- 65 tion with a source of fuel under pressure and with the interior of the retort at right angles to the path of incoming air entering the retort from the exhaust pipe 22. A spark plug 24 or other suitable igniter is let through the walls of the condenser and re- 70 tort. The blower 21 has its inlet in communica- 75 tion with a hopper 25 or other suitable source of finely divided ore which is to be treated. It will be obvious that ore drawn into the intake of the fan is passed through the exhaust pipe 22, entering the retort 10 tangentially, with the result that it has a whirling or rotating motion within the re- 80 tort and expands centripetally. Incoming air and ore striking the incoming fuel 85 which is admitted at right angles thereto finely divides the same and this fuel is either ignited by the igniter 24 or after a predetermined operation, during which the interior of the retort becomes highly heated by spontaneous combustion, with the result that the finely divided ore, intermingled with the whirling air, during its downward passage through the retort, is very highly heated. The temperature for the ores referred to is 90 preferably about 1,000° C., or that temperature at which the base metals contained in the ores are oxidized.

95 Within the upper conical extension 15 of the condenser is arranged a spray head 26 forming a spray which passes downwardly over the sides of the retort shell 12, cooling the same, and washes gases passing upwardly between the retort shell and the opposed wall of the condenser. This water, together 100 with precipitated roasted ores, collects in the lower conical extension 16 and is maintained at a level therein such that a small space is left between the lower end of the retort and the surface of the water. This water 105 and the contained ores is continually drawn off through a valve 27 by the outlet 18, the rate of removal being such that the water level is kept at the proper height.

110 It will also be obvious that in cooling the

gases and ores, a portion of the water will be converted into steam and the gases will still retain a large proportion of their heat.

These heated gases, together with the contained steam, are led to a commercial sulphuric acid plant, thus eliminating the necessity for adding steam to the gases at the plant as a step in the production of the acid. In their passage, they preferably pass about 10 the exhaust pipe 22 of the blower 21 which is of approximately one-half the diameter of the condenser outlet 17 and partially housed therein.

It is pointed out that by the use of finely divided ores, which should be of such size that they will pass through a one hundred mesh screen, the roasting process is substantially instantaneous and is not dependent upon the length of time that the ores remain 20 in the retort 10, with the result that the pressure or speed of the blower 21 is not critical. Furthermore, when these ores are introduced at a very high speed, with the result that they pass through the retort at a high 25 speed, the blower action causes a finer division of the fuel and a hotter flame within the retort, so that the construction employed is substantially compensating and the temperature will vary with the speed of operation 30 to insure proper roasting. It is pointed out that in the roasting of gold bearing sulphide ores, the contained sulphur provides fuel which, after the retort is heated to a predetermined extent, becomes active and 35 enables a considerable reduction of the input of fuel to the retort. This is particularly true where the material is finely divided. It has been found that by use of the method employed, stack gases are chemically free 40 from gold, the heavier particles of which are precipitated when the gases make their abrupt change of direction in passing from the retort into the condenser space and the lighter particles of which are washed from 45 the gases by the cooling liquid which engages thereagainst at the time of their change of direction and for a considerable period thereafter.

Since the construction hereinbefore set 50 forth is capable of a certain range of change and modification without materially departing from the spirit of the invention, I do not limit myself to such specific structure except as hereinafter claimed.

55 I claim:—

1. In apparatus for roasting ores and in combination, an open-bottomed vertically extending cylindrical retort, means for introducing air under pressure with which the 60 ore to be roasted is finely intermingled to said retort at the upper end thereof and at such an angle as to produce rotation of the incoming air and ore, means for introducing fuel to the retort in the path of the incoming 65 air and ore and means for washing gases

passing from the lower end of the retort and for collecting ores removed by the washing process.

2. In apparatus for roasting ores and in combination, an open-bottomed vertically extending cylindrical retort, means for introducing air under pressure with which the ore to be roasted is finely intermingled to said retort at the upper end thereof and at such an angle as to produce rotation of 75 the incoming air and ore, means for introducing fuel to the retort in the path of the incoming air and ore, a casing surrounding the retort in spaced relation to the walls thereof and having at its upper end an outlet and at its lower end an inlet, means at 80 said upper end for delivering a spray of cooling liquid and means at the lower end controlling the passage of liquid and ores from the lower end to maintain a predetermined liquid level therein.

3. In apparatus for roasting ores and in combination, an open-bottomed vertically extending cylindrical retort, means for introducing air under pressure with which the ore to be roasted is finely intermingled to said retort at the upper end thereof and at such an angle as to produce rotation of the incoming air and ore, means for introducing fuel to the retort in the path of the incoming air and ore, a casing surrounding the retort in spaced relation to the walls thereof and having at its upper end an outlet and at its lower end an inlet, means at 90 said upper end for delivering a spray of cooling liquid, means at the lower end controlling the passage of liquid and ores from the lower end to maintain a predetermined liquid level therein and means for conducting 95 exhaust gases passing from the upper end 100 of the casing about the inlet for the retort to preheat the air and ore introduced thereto.

4. In apparatus for roasting ores and in combination, an open-bottomed vertically extending cylindrical retort, means for introducing air under pressure with which the ore to be roasted is finely intermingled to said retort at the upper end thereof and at such an angle as to produce rotation of the incoming air and ore, means for introducing fuel to the retort in the path of and at 110 right angles to the incoming air and ore and a washing condenser surrounding the retort and combining therewith to provide 115 a conduit for gases passing from the lower end of the retort.

5. In apparatus for roasting ores and in combination, an open-bottomed vertically extending cylindrical retort, means for introducing air under pressure with which the ore to be roasted is finely intermingled to said retort at the upper end thereof and at such an angle as to produce rotation of the incoming air and ore, means for introducing 125 130

- fuel to the retort in the path of and at right angles to the incoming air and ore, a washing condenser surrounding the retort and combining therewith to provide a conduit for gases passing from the lower end of the retort, whereby the gases are caused to pass upwardly about the sides of the retort and means for washing the gases during their movement through the passage. 5
- 10 6. In apparatus for roasting ores and in combination, an open-bottomed vertically extending cylindrical retort, means for introducing air under pressure with which the ore to be roasted is finely intermingled to said retort at the upper end thereof and at such an angle as to produce rotation of the incoming air and ore, means for introducing fuel to the retort in the path of and at right angles to the incoming air and ore, a washing condenser surrounding the retort and combining therewith to provide a conduit for gases passing from the lower end of the retort whereby the gases are caused to pass upwardly about the sides of the retort, means for washing the gases during their movement through the passage, means at the lower end of the condenser for collecting precipitated ore and the washing fluid and means controlling the passage of the washing fluid and ore from the last named means to thereby maintain the level of the washing fluid at a predetermined distance from the lower end of the retort. 25
- 15 In testimony whereof I hereunto affix my signature. 30

DANA W. BOWERS.
